UNITED STATES PATENT OFFICE.

JAMES L. PARRISH, OF VALDOSTA, GEORGIA.

HAME.

Application filed June 8, 1922. Serial No. 566,820.

To all whom it may concern:

- Be it known that I, JAMES L. PARRISH, a citizen of the United States, and resident of Valdosta, in the county of Lowndes and 5 State of Georgia, have invented certain new and useful Improvements in Hames, of which the following is a specification, reference being had therein to the accompanying drawing.
- 10 This invention relates to hames, and its object is to improve hames of a common general type without materially increasing their cost.
- In the accompanying drawings,
- 15 Fig. 1 is a side or point view showing a hame embodying my invention.
- Fig. 2 is a section on the line 2—2, Fig. 1.
- Fig. 3 is a view in the direction of the arrow of Fig. 1.
- 20 In ordinary hames of this type, the body is of wood, having its outer margin reinforced with a metal strip, secured by rivets, passing through the metal and wood, and at the proper point a staple passes through 25 the wood parallel to the margin and riveted in place. Upon the loop of this staple—which has a slight offset, is mounted a bracehook, and below it on the offset portion, a ring. The rivet and staple greatly weaken 30 the hame in this region where most of the strain is applied, and for this reason hames frequently break at this point, and practically never break elsewhere. This invention makes this weak point far stronger than 35 any other portion.
- In the construction shown, 10 represents the wood portion of a hame and 11 a steel strip covering its outer margin, which is practically perpendicular to the plane of the 40 inner or back face. The wood member 10 is largest in the region where the main strain is to act, but has in this region no perforations whatever, and the strip 11 has here its maximum thickness. The strip is 45 secured to the upper and lower portions of the wood member in the usual way. Over the upper slightly tapering portion of the hame is slipped a heavy metal sleeve 12, provided at a short distance in front of its rear face with integral spaced lugs 13, 50 through which passes a bolt 14, and upon this bolt between the lugs is loosely mounted a trace hook 15, which in use may swing back against the flat edges of the sleeve. The lower lug 13 has its upper side 13' 55 rounded to receive the primarily pendant ring 16, lying between the bolt and sleeve, and allowing it to swing, while resting on the lug surface which it approximately fits. The strip in the region where the sleeve is 60 to lie is slightly increased in thickness in passing downward, and its edges are preferably very slightly undercut at 11' to receive the corresponding part of the sleeve, and both the wood and strip are fitted to 65 the interior slightly tapered sleeve when the latter is a little above its desired position. The sleeve is then highly heated, slipped over the hame, and quickly driven down to proper position and at once cooled before 70 it can materially burn the wood. In cooling, it of course, shrinks, and strongly and permanently grips the hame. In shrinking, it grips the undercut metal strip independently of shrinking and swelling of 75 the wood.
- Obviously this heavy sleeve, which extends to some distance above and below the trace hook, makes the hame at this point many times stronger than at any other point 80 or than an ordinary hame. It is also to be noted that the drilling and riveting in the region of great strain is avoided. Should it break at any other point, the sleeve may be used again. 85
- What I claim is:
1. A hame provided with a heavy slightly tapered metal strip on its outer margin, a metal sleeve encircling the hame adapted to be forced while hot over said hame and on cooling to grip edgewise said metal strip, and trace attaching devices carried by said sleeve. 90
  2. A hame having a wood body provided with a slightly tapered heavy metal strip on its outer margin, a heavy metal sleeve adapted to be forced while hot over a larger region of the hame and on cooling to grip edgewise 95

said metal strip whether or not the wood portion shrinks, and trace and strap attaching devices carried by said sleeve.

3. In a hame, the combination with a
5 wood body having on its outer margin a slightly tapered heavy metal strip provided with a portion over which a sleeve may be passed merging into a second slightly larger identically similar portion integral

with the first, of a metal sleeve adapted to 10 slip over the first portion and to be forced, when heated, over the second portion and on cooling to grip the wood and also to grip edgewise the metal strip whether or not the wood shrinks. 15

In testimony whereof I hereunto affix my signature.

JAMES L. PARRISH.
